INVENTOR:

Edward Cairns,
By *W. W. Swanson*,
His ATTORNEY

UNITED STATES PATENT OFFICE

EDWARD CAIRNS, OF MONTCLAIR, NEW JERSEY

HELMET

Application filed May 6, 1932. Serial No. 609,621.

This invention relates to headgear, being especially adapted for firemen's helmets, although being applicable to other types of hats and has for its objects the provision of a light, sturdy, one-piece ornament that is adapted to bridge the space between the comb on the top of the helmet and the top of the shield and to securely retain and center the upper end of such shield, thereby preventing accidental displacement thereof, besides lending itself to accommodate ribs and combs of different sizes. Heretofore it has been customary to mount an ornamental figure, such as an eagle's head, a fox, beaver, snake, etc., at the top of the front shield of a fireman's helmet, the same having been usually made of two symmetrical embossed halves soldered together and a vertical pin was often driven into the top of the leather shield and through the front end of such figure in order to center and retain the shield against lateral displacement. Such ornaments, however, in use, especially if struck by falling objects tended to readily split open at the soldered joint, often becoming loose, and it is accordingly necessary to entirely replace or repair the same. To avoid the objections possessed by such ornament, it has been proposed to cast them the same as an integral piece, but these cast ornaments were objectionably heavy and, furthermore, the uniform slot which was formed in such casting for the reception of either the comb or the rib of the helmet did not satisfactorily fit the varying sizes of combs or ribs of different hats and owing to the nature of the cast material, it was virtually impossible to fit the ornament thereto by bending the sides thereof because of the inherent brittleness of such castings.

My investigations led to the discovery that if such ornament is formed in one-piece by stamping up the same from light sheet metal, such as sheet brass, the various objections possessed by all prior ornaments for firemen's helmets can be eliminated and such one-piece ornament is furthermore cheap, will have all its exposed surfaces smooth and withal will possess an extremely attractive appearance, besides lending itself to being

emblazoned or embossed with suitable insignia.

My invention is fully described in the following description and drawing forming a part thereof, in which

Figure 1 is a plan view and Fig. 2 is a longitudinal side elevation, partially in section, of a fireman's helmet equipped with my improved ornament;

Fig. 3 is a horizontal section on the line 3—3 of Fig. 2 and

Fig. 4 is a perspective view of my improved ornament or bridge member, isolated.

Referring to the drawing and the construction shown therein, the reference numeral 1 designates the crown or body member of a fire helmet and 2 the brim thereof. As shown, the crown is provided with combs or ribs 3 formed by sewing together the adjacent up-turned edges of the adjacent sections which form the helmet and at the intersection thereof at the top of the hat, the usual comb cover or cap is provided, whose projecting arms 4 conform to a Greek cross and are adapted to snugly embrace the alternate rib members 3, being riveted thereto by means of rivets. The body 6 of said cover is of bell or dome shape and projects to within a short distance, preferably but a small fraction of an inch of the crown of the hat, thereby permitting the ventilation of the same through the vertical ducts 7. The usual shield 8 is secured to the front end of the crown by means of rivets 9, the same being adapted to have emblazoned thereon or otherwise secured thereto suitable insignia or ornamentation (not shown), such for example as that designating the particular fire department and the particular engine company thereof. As shown, said shield is of arcuate horizontal cross section, the same being reinforced by a metallic bow or arcuate brace 10, that serves to preserve such arcuate configuration particularly at the upper end of the shield.

An ornament or bridge element 11 interconnects the top of the shield and front rib of the helmet, the bridge preferably being of sheet metal construction and being formed from a single piece of metal by stamping up a sheet to form opposing, substantially par-

allel, side members 12, 12', which terminate at their bottom 13, 13' in substantial points, and a projecting hollow terminal hook member 14, which terminates in a very thin edge 15 and also has opposing, substantially parallel, side members 16. Said ornament embraces the central front rib 3 of the hat and also receives the top pointed end *a* of said shield member 8, besides also having oblique faces *b*, *b'* that are adapted to bear against and reinforce the brace or bow 10. The upper end of the shield 8 is formed into a point and is adapted to project into the space *c* between the opposing sides 16 of said hook member, thereby securely centering the latter and preventing its lateral displacement without requiring the mutilation of the end of the shield by driving a pin thereinto in the manner heretofore customary. The rear 20 of said bridge member is preferably embraced by the front arm of the comb cover and a grommet *d* serves to hold said cover, the rear end of the bridge and such rib in an assembled relation. As shown, said bridge member is also secured to rib 3, at its lower front end by another grommet *d'*.

The front edges *b*, *b'* of the bridge proper are parallel with each other and oblique with respect to the vertical edges thereof and, as 30 stated, are adapted to abut against the brace 10. The lower edges *g* of the sides 12, 12' are preferably on the other hand, of identical curvature, corresponding generally to the outer curvature of the front of the helmet 35 from the comb cover at the top of the dome to the point of the disappearance of the crown behind the shield, whereby stock size of the bridge can be readily fitted to hats having crowns of different sizes, since it is merely 40 necessary in applying the bridge, to secure the same to the front comb so that the terminal hook projects into a predetermined position with respect to the brim of the hat and thereupon the shield is secured to the hat 45 and the top end has been inserted into the recess *c*. If the rear end of the bridge, when applied to a small hat, extends back too far to be received beneath the front arm of the comb cover, it is merely cut off to the extent necessary. It is desirable that the lower 50 edge 15 of the hook 14 be relatively thin so that it can be caused to bite into and firmly grip the leather, which is the customary material of the shield and thereby it will more effectively anchor the same against movement.

Various changes within the scope of the appended claims may be made without departing from the spirit of my invention.

Having thus described my invention, what I claim and desire to obtain by United States Letters Patent is:

1. In a helmet, the combination comprising a crown having converging ribs and having a central comb cover at the point of junc-

ture of the ribs, one of said ribs projecting forwardly and centrally, an upward extending shield member secured to the front of the crown and a sheet metal bridge member having a closed top and depending, substantially parallel sides embracing that portion of the edge of such rib which would otherwise be visible between the top edge of the shield and the comb cover and said bridge member having a hollow hooked portion in engagement with the extreme top of said shield and said bridge member being secured to said forwardly projecting rib.

2. In a helmet, the combination comprising a crown having a forwardly projecting central rib, an upwardly projecting shield having a pointed upper end secured to the front of the crown, and a unitary bridge member formed of a single piece of sheet metal, having a closed top and depending substantially parallel sides, embracing that portion of the outer edge of such rib not hidden by such shield and the front end of said bridge member being channelled and extending downwardly across the top portion of said shield and the top end of said shield projecting into the channel in the front end of said bridge member and the extreme end of the front end of said bridge member being in snug engagement with said shield adjacent the tip thereof, whereby said shield is securely held against dislodgment from said bridge member.

3. In a helmet, the combination comprising a crown having converging ribs, an upwardly projecting shield having a pointed top end secured to the front of the crown, a unitary bridge member formed of a single piece of sheet metal, the same being of U-shaped cross-section and having a closed top and substantially symmetrical depending sides, the lower edges of said sides being arcuate, and the lower portion of the front edges of said sides extending obliquely to the upper portion of such front edges, said bridge having a channelled terminal hook member which extends across the top end of said shield and downwardly over the front face thereof adjacent said top end and the extreme tip of said hook snugly engaging the front face of said shield and the said top end of said shield projecting into the space between the sides of the channelled hook member.

4. In a helmet, the combination comprising a crown having a central, forwardly extending rib, an upwardly extending shield, curvilinear in horizontal cross-section, secured to said crown, a brace for maintaining the curvilinear cross-section of said shield and a bridge member, formed of sheet metal and having depending sides, interconnecting the top of said shield and said rib, the sides of said bridge abutting at their lower front edges against said brace and the lower edges

of said sides being of a curvilinear configuration substantially conforming to that of the adjacent portion of the crown.

5. In a helmet, the combination comprising a crown having a central, forwardly extending rib, an upwardly extending shield, having a pointed upper end and curvilinear in horizontal cross-section, secured to said crown, a brace for maintaining the curvilinear cross-section of said shield and a bridge member, formed of a single piece of sheet metal and having a closed top and depending sides, interconnecting the top of said shield and said rib, the sides of said bridge abutting at their lower front edges against said brace.

10 15 Signed at New York, in the city, county and State of New York, this 4th day of May, 1932.

EDWARD CAIRNS.
